SHUTTLE TENSION

Edward Bloom, Paterson, N. J.

Application April 19, 1933, Serial No. 666,793

1 Claim. (Cl. 139—214)

The filling tension mechanism usually employed in shuttles in which silk or artificial silk is used has heretofore comprised a row of fixed pins driven into the shuttle body from the top and a spring-resisted lever having eyelets to alternate with these pins when the filling, trained back and forth zig-zag fashion with respect to the pins and eyelets, was under draft, as in the flight of the shuttle. These pins work out so as to project from the shuttle and become a dangerous menace to the warp. One object of my invention is to provide a shuttle with a tension mechanism in which these pins will be dispensed with. Another object is to provide a shuttle tension mechanism which shall preserve the desired tension on the filling without unduly chafing or wearing the same and with as little wear of the filling engaged parts of said mechanism as possible and which tension shall be as nearly equable as possible during the flight of the shuttle. In carrying out this object I employ two cooperative tension means, to wit, a primary one which includes a spring and thereby tends to hold the yarn with a bend therein and yields on a pull on the yarn and a secondary one which frictionally resists slippage of the yarn lengthwise of itself, the resistance of the primary one being less than that of the secondary one so that whereas the full tension is mainly dependent on the slip-friction of the secondary one the yarn gradually assumes the state of full tension when the shuttle starts on its flight.

In the drawing,

Fig. 1 is a horizontal fragmentary sectional view of a shuttle embodying the improved tension mechanism;

Fig. 2 is a side elevation thereof; and

Fig. 3 is a plan, partly in section, illustrating a modification.

The shuttle body 1 has the usual cavity 2 for the quill 3 or other core for the wound weft package and forward of said cavity an opening 4 is formed which extends clear through the body from side to side, the cavity and opening having communication with each other through an eyelet 5.

In the opening 4 is arranged the mentioned primary tension means, to wit, one which includes a spring and tends to hold the yarn with a bend therein and yields on a pull on the yarn, the same comprising a yielding member having a thread eyelet or eyelets, a spring yieldingly opposing its movement and means to confine it to movement in a definite path. Said member is here a slide in the form of a block 6 having eye-

lets 7 for the thread and movable back and forth generally lengthwise of the shuttle. The means to confine said member to movement in a definite path—here rectilinear—is a pin 8 which is entered to opening 4 from the near side in Fig. 1 and has one end seated in a hole 9 in the shuttle body and its other end provided with an eye 8a penetrated by a device 10 which is here a screw screwed into the shuttle body from the top thereof. (Instead of pin 8 having an eye to receive the screw, it may have a hook 8b, as in Fig. 3). The spring is shown at 11, being coiled about the pin and having one end clamped between two annular shoulders 8c thereof and its other end entered into the member 6. The spring 11 exerts no torsional action on member 6, which in any event is kept from turning on the pin by having its flat top and bottom faces closely related to the top and bottom surfaces of opening 4, as shown in Fig. 2. Thus the fixed structure 20 of the shuttle, including the guide, confines the slide against all angular displacement.

The weft or filling *a*, extending through eyelet 5, reaches through the eyelets 7 of member 6 and then back to the eyelet outlet 12 of the shuttle body, being normally thus maintained in a bend by the action of the spring to urge said member forward against the front surface of opening 4.

In the front end of cavity 2 is the mentioned secondary tension means which frictionally resists slippage of the yarn lengthwise of itself, being here and preferably immovable lengthwise of the yarn. It is in effect a clamp. In the example, one member of this clamp is fixed and consists of a U-shaped metal strip 13 which straddles a portion 1a of the shuttle body formed to project into the cavity from one side thereof. The other member is a U-shaped strip 14 arranged with its convex side facing the convex side of the member 13 and slidable toward and from said member on a pin 15 driven into the side of the shuttle body and into projection 1a, penetrating member 13, member 14 being kept from turning on pin 15 by bearing against the bottom of the cavity. The clamping pressure may be obtained by any elastic means acting on member 14, but I prefer for this purpose to interpose a piece of sponge rubber 16 between member 14 and the outer side of the cavity, it being kept in place by being arranged under pin 15.

The filling *a*, between the quill 3 and eyelet 5, extends between the brake members of the secondary tension means.

The principal tension means is what I have termed the secondary one in that it resists to a greater degree and more steadily the slippage of the filling during the flight of the shuttle than the primary tension means, which latter acts initially, or when the shuttle starts its flight, to cause the ultimate degree of tension to be assumed gradually and which also acts upon the shuttle coming more or less quickly to rest at the end of its flight as a take-up for the filling, so that the latter is then kept taut. To these ends it is desirable that the parts of the two means be arranged so that the filling extends substantially straight from the endwise-delivery package to the guiding medium (eyelets 7) of the primary means and that the movability with respect to the latter means be as nearly as possible lengthwise of this substantially straight portion of the filling.

20 When the eyelets 7 become worn the member 6 can be removed and replaced with a new one

or provided with new eyelets by removing screw 10 and withdrawing pin 8. The strips 13-14 of the secondary tension means can also be removed and replaced, if they become worn, by removing pin or screw 15.

5

Having thus fully described my invention what I claim is:

In combination, a shuttle body having an opening at one side thereof and a hole reaching from said opening, said body also having a filling outlet, a wound package in said body, a pin in said opening having one end entered into the hole, a filling guiding and tensioning member slidable on the pin and normally maintaining a bend in the filling between the package and outlet, a spring resisting movement of said member in the direction to straighten said bend, and removable means engaging the pin and retaining it in the hole.

EDWARD BLOOM. 20
